Primary Examiner — Karen S Acker

(74) Attorney, Agent, or Firm — Davis Wright Tremaine LLP

(57) CLAIM

The ornamental design for a fabric with camouflage pattern, as shown and described.

DESCRIPTION

The patent or application file contains at least one drawing executed in color. Copies of this patent or patent application publication with color photograph(s) will be provided by the Office upon request and payment of the necessary fee. The sole FIGURE is a front elevation view of a fabric with camouflage pattern showing our new design.
